FOREIGN PATENT DOCUMENTS

GB 814686 6/1959

Primary Examiner — Susan Moon Lee(74) *Attorney, Agent, or Firm* — Alvin T. Rockhill**CLAIM**

The ornamental design for an animal feeder which is particularly suitable for feeding deer, as shown and described.

DESCRIPTION

FIG. 1 is a front-top perspective view of an animal feeder which is particularly suitable for feeding deer.

FIG. 2 is a front-bottom perspective view of the animal feeder. FIG. 3 is a front view of the animal feeder with the back view being identical to the front view.

FIG. 4 is a right side view of the animal feeder with the left side view being identical to the right side view.

FIG. 5 is a top view of the animal feeder; and,

FIG. 6 is a bottom view of the animal feeder.
